UNITED STATES PATENT OFFICE.

HARRY I. MUUS, OF VANCOUVER BARRACKS, WASHINGTON.

DRIP SHIELD FOR SHAVING BRUSHES.

Application filed October 16, 1923. Serial No. 668,879.

To all whom it may concern:

Be it known that I, HARRY ISAKSON MUUS, a citizen of the United States, and a resident of Vancouver Barracks, in the 5 county of Clarke and State of Washington, have invented certain new and useful Improvements in Drip Shields for Shaving Brushes, of which the following is a specification.

- 10 This invention relates to an improvement in drip shields for shaving brushes, and has for its object to provide a device of this character which is designed and adapted to receive the excess of water from the brush 15 so as to prevent the same from flowing, dropping or working down onto the hands or clothing of the person shaving or from dropping upon and soiling surrounding objects and which is at the same time adapted 20 for ready attachment or association with the brush.

A further object is to provide a device 25 of this character having the foregoing advantages and capacities and which when associated with the brush in no way detracts from the capacities or advantages of the brush, the shield being at the same time unbreakable and efficient and effective to carry out its intended purposes.

- 30 A further object is to provide a shield of this character which is so constituted as to provide for the support of the brush upon a shaving mug in such manner that the bristles are suspended above the water in the 35 mug so as to prevent excessive absorption of water, the shield being at the same time adapted to support or position the bristles of the brush spaced from and above the surface of a table, stand or the like so as to 40 prevent soiling of the same when a brush is laid or rested upon such a support.

Other objects and advantages of the invention reside in certain novel features of the construction, combination and arrangement 45 of parts which will be hereinafter more fully described and particularly pointed out in the appended claims, reference being had to the accompanying drawings forming part of this specification, and in 50 which:

Figure 1 is a perspective view, showing one embodiment of the invention;

Figure 2 is a view, partly in elevation and partly in section of the embodiment 55 shown in Figure 1;

Figure 3 is a view similar to Figure 2 but

showing the shield supported or related to the brush in a slightly different manner; and

Figure 4 is a fragmentary view similar to 60 Figure 3, and showing a slightly modified form of the invention.

Referring to the drawings wherein for the sake of illustration is shown the preferred embodiment of the invention, the numeral 10 designates generally a shaving brush which includes a handle 11, a ferrule or bristle mounting 12 and bristles or tufts 13. Usually there is provided between the ferrule 12 and handle 11 an annular 70 shoulder or rib 14.

Referring now especially to Figures 1 to 3, inclusive, it will be seen that the drip shield which constitutes the present invention is constructed of soft rubber or other 75 suitable material which is elastic and yet at the same time possesses sufficient rigidity in assembly to enable it to carry out the functions hereinafter set forth. The shield comprises a shell 15 of spheroidal form and 80 having its ends open. One end of the shield terminates in a flat rim 16 which is in-turned or provided with an inner peripheral flange and the opposite end thereof is extended and reduced to provide an attaching 85 nipple 17. In assembling the shield with the brush this nipple 17 must be stretched or distended, and the arrangement is preferably such that even in the assembly as shown in Figure 2 the nipple 17 is still 90 slightly stretched so that by virtue of the elasticity or resiliency of the material of which it is composed it tightly grips the handle 11 of the brush and provides the attaching means necessary for holding the 95 shield in position on the brush.

In Figure 3 the nipple 17 is shown as in-turned and frictionally engaged with the ferrule or brush member 12. The structure of the shield is identical with that shown 100 in Figures 1 and 2 but before assembling the same with the brush its nipple is in-turned and is stretched over the ferrule 12 instead of over the handle 11. In other respects the shields are identical and, as shown in 105 the drawings, each includes a plurality of lugs 18 arranged around the rim 16 of its shell. When the brush is supported on the shaving mug or vessel, its rim rests on the rim of the shaving mug and the lugs 18 prevent displacement of the rim 16 therefrom. 110 In the form of the invention shown in

Figure 4 the shield is constructed of soft rubber or other elastic material and includes a shell of spheroidal form, as designated at 20 and has one of its ends terminating in a 5 flat and inturned or flanged rim 21 provided with lugs 22 corresponding with the rim 16 and lugs 18, respectively. The opposite end of the shield from that at which the rim 21 occurs is thickened, as at 23, to provide a 10 slight nipple 24 and inwardly of the nipple it is formed with an annular shoulder 25. As in the arrangement shown in Figure 2 the nipple 24 engages the handle 11 but only a slight area or portion of the same and the 15 action of the nipple 24 is supplemented by the engagement of the shoulder 25 with the rib 14. The nipple 24 and rib 25 are so constituted with respect to the handle 11 and rib 14 that in the assembly as shown in 20 Figure 4 they are under tension and by virtue of their inherent elasticity or resiliency they tightly and frictionally engage the handle 11 and rib 14, respectively. It will be understood from a comparison of Figures 2 and 3 that it is possible to embody 25 the invention in an arrangement in which the nipple 17 is of a very slight size or extent and in fact the nipple may be entirely dispensed with and the inner wall of the 30 opening at the inner end of the shell may alone provide a gripping surface of sufficient area to frictionally engage the brush and hold the shield in position thereon.

In use, the large open end of the shield 35 which is defined by the rim 16 or rim 21, as the case may be, surrounds the bristles or tufts adjacent their mounting 12 and the spheroidal shell provides a relatively large cup or container which is arranged and 40 adapted to receive the excess of water carried by the bristles. Moreover, the spheroidal form of the shell in connection with the inturned or flanged rim tends to hold and trap this liquid even when the brush is laid 45 upon a table, stand or other flat support. The inturned or flanged rim has the further function of stiffening and reinforcing the shell to provide a relatively stable and rigid shell without necessitating a bulky and 50 heavy construction. It is to be noted, that when the brush is so positioned, that the

bristles or tufts will be held above and out of contact with the surface of the table or stand, since the brush will rest on the crest of the convexity of the shell and upon the 55 outer end of its handle 11. The shield being constructed of soft rubber is unbreakable and being curved and arranged to blend in with the lines of the brush does not detract from the appearance or balance thereof. The lugs 18 or 22, as the case may be, assist in supporting the brush on the shaving mug or vessel when the same is not in use and in such manner that it does not dip into the water therein thereby preventing 60 excessive absorption. Preferably the inner faces of these lugs are recessed, as indicated at 18 and 22 respectively, to better adapt them for engagement with the rim of the mug or shaving vessel. Of course it will be 65 understood that these lugs may take any desired shape or form.

While I have herein shown and described the preferred embodiments of the invention it is to be understood that I do not limit 75 myself to the precise construction herein shown as various changes in the form, proportion and minor details of construction may be resorted to without departing from the spirit and scope of the invention and the 80 subjoined claims.

I claim:

1. A drip shield for use on shaving brushes and comprising a shell positioned on the brush and having its open end encircling the bristles of the brush, the rim of the shell which defines said open end having a plurality of lugs provided with recessed inner faces, said rim and said lugs being adapted to coact with the rim of a shaving mug or 90 other support for supporting the brush.

2. A drip shield for use on shaving brushes and comprising a shell positioned on the brush and having its open end encircling the bristles of the brush, the rim of the shell which defines said open end having a plurality of lugs, said rim and said lugs being adapted to coact with the rim of a shaving mug or other support for supporting the brush.

HARRY I. MUUS.
